UNITED STATES PATENT OFFICE.

GEORGE PERCY SMITH, OF YOUNGS COVE, NEW BRUNSWICK, CANADA.

TACK-DRAWER.

1,043,369.

Specification of Letters Patent.

Patented Nov. 5, 1912.

Application filed September 18, 1911. Serial No. 649,044.

To all whom it may concern:

Be it known that I, GEORGE PERCY SMITH, a subject of the King of Great Britain, residing at Youngs Cove, New Brunswick, Canada, have invented new and useful Improvements in Tack-Drawers, of which the following is a specification.

This invention relates to certain novel improvements in tack drawers.

10 In carrying out my invention it is my purpose to provide a tack drawer which embodies the desirable features of simplicity and cheapness, and which provides means for recovering the withdrawn tacks and depositing the same within the hollow handle of the drawer.

I also aim to provide a device of this class which may be operated by one hand of the user, the said operation including the withdrawal of the tack, as well as the depositing of the tack within the handle of the drawer.

20 A further object of the invention is to simplify and to improve the existing art by providing a device of this class which is simple, inexpensive, and which may be readily and easily operated, which comprises few parts and which may be manufactured at a minimum cost.

With these objects, and others of a similar nature in view, the invention resides in the novel construction, combination and arrangement of parts set forth in and falling within the scope of the appended claim.

In the drawings,—Figure 1 is a perspective view of a tack drawer constructed in accordance with the present invention. Fig. 2 is a central longitudinal sectional view of the same. Fig. 3 is a transverse sectional view taken upon the line 3—3 of Fig. 1.

40 In the drawings, the numeral 1 designates generally the improved tack drawer. This drawer 1 comprises a handle 2 which is hollow to provide a compartment 3, and the said compartment is normally closed through the medium of a cap 4. The numeral 5 designates the shank of the drawer, which in the present instance has been illustrated as being formed integrally with the handle 2. The extremity of the drawer is provided 50 with the tack lift proper 6, the same being constructed of some suitable metal, and having its outer face inclined and projecting above its top proper, the said inclined portions being centrally provided with a V-shaped slot 7 whereby the prongs 8 adjacent the said slot may be inserted around the tack

so as to bring its head between said prongs and to be removed by the prongs and deposited within the passage 8 formed by the shank 5, the upper face of the lift 6, and a sheathing of metal which is designated by the numeral 9. The lift 6 has its lower face provided with an enlargement or head 10, the latter serving as a fulcrum point upon which the device is swung to raise the tack. It will be noted that a slide space is left between the prongs 8 and the metallic sheathing 9, so that upon the elevating of the drawer, the tack will be permitted to pass through the passage 8 to within the opening 70 of compartment 3 provided by the handle 2.

The numeral 11 designates a door which may be mounted in suitable bearings and which normally closes the passage 8. This door 11 is provided with a bar 12, the latter 75 being pivoted as at 13 to the wall provided between the compartment 3 and the passage 8.

Loosely connected with the bar 12 is a pin 14, the same passing through a suitable passage in the handle and having its outer extremity provided with a head 15. The numeral 16 designates a spring which surrounds the pin 14, and exerts a pressure between its head 15 and the handle 2 of the 85 drawer, and which normally closes the door 11 and the passage 8.

From the above description, taken in connection with the accompanying drawings, it will be noted that when a tack is drawn, 90 as previously described, the said tack, upon the elevation of the drawer will slide down the passage 8 and contact with the door 11. Upon the downward movement of the pin 14, the door 11 will be opened thus permitting the tack to enter the compartment 3.

This arrangement prevents the clogging of the tacks within the passage 8, and when a sufficient amount of tacks are received within the compartment 3, the cap 4 may be 100 removed and the said tacks passed through the reservoir 2 to a desired receptacle.

Having thus fully described the invention, what I claim is:—

A tack drawer including a handle which 105 is integrally formed with a reduced longitudinally extending shank, the handle containing a chamber provided with a removable closure, the wall of the chamber adjacent the shank being arranged at a right 110 angle to the upper face of the said shank, a door for closing the opening between the

shank and the chamber, said door comprising a flattened member, a link secured to the door and pivotally connected to the said wall of the chamber, a headed rod passing through an opening in the handle and loosely connected with the link, an expansion spring between the head of the rod and the handle, a sheathing secured to the handle and the opposite sides of the shank, and an

angular forked tack lifter secured to the 10 end of the shank.

In testimony whereof I affix my signature in presence of two witnesses.

GEORGE PERCY SMITH.
